6 Claims. (Cl. 28—55.5)

1

This invention relates to a rewinder for use in rewinding bobbins, or other yarn carriers, after a length of yarn has been unwound and severed. The invention is applicable generally for the purpose specified but will be hereinafter described as applied for the purpose of rewinding of bobbins or other yarn carriers used for setting spools for use in the production of pile fabrics wherein the pile yarns are wound upon spools from which short lengths of the yarn are severed and successively inserted in the fabric to form the pile tufts.

In carrying out this manufacture, it is the usual practice to use a separate spool for each row of the design and wound upon the spool are a number of lengths of yarn corresponding with the number of units in the row of design. The operation of arranging and winding the coloured yarns on to the spools is known as spool-setting and is usually carried out by using a creel or table upon which are a number of rows of pegs, each adapted to receive a bobbin or cheese wound with yarn, and in front of which is a spool winding machine known as a setting frame. The creel or table may be horizontal, inclined or vertical. Between the creel and the setting frame is fixed an open comb having the same number of openings as there are units in a row of design, and mounted in a convenient position is a diagram of the design, this diagram being prepared on squared paper and the squares being coloured to correspond with the design.

Bins, shelves or other suitable receptacles are provided adjacent the creel or table containing bobbins or cheeses wound with yarn of the colours required, and the operators proceed by first consulting the design diagram, then selecting one or more bobbins for the first one or more units in the first row of the design and placing them on the appropriate pegs. This operation proceeds until the row is complete, and the ends of the yarn on the various bobbins are drawn forwardly through the appropriate openings in the stationary comb and thence to the spool to which the ends are attached. The spool is then rotated until sufficient yarn is wound off and the yarn is severed. One or more additional spools of the same yarns may then be wound and severed according to the length of fabric to be woven.

The operators then proceed to deal with the next row, an operation which involves removing all those bobbins corresponding with units which are not of the same colour as the corresponding units in the previous row, and subsequently replacing them by further bobbins having yarn

2

of the colour required for those units in the second row.

In spool-setting in the manner described when a spool has been loaded with yarn and the yarns have been severed, it is necessary to rewind those bobbins on the creel where the colours are to be changed for the next row. Hitherto this has been done by hand and the rewinding operation has occupied a considerable time and is the cause of considerable fatigue to the operators.

The object of the present invention is to reduce the time occupied and to eliminate the fatigue produced by rewinding operations.

According to the present invention we provide 15 rewinding gear comprising a rewinder unit including a body having a power driven rotary driving member which can be made to engage and drive any one bobbin or yarn carrier to effect rewinding.

20 As applied to spool setting the rewinding unit may be flexibly and resiliently suspended above a creel so that it can be brought into position to act on any of the bobbins or yarn carriers thereon.

We may for instance provide one or more supporting rails above the creel upon which or upon 25 each of which a movable carriage is provided, upon which is suspended a rewinder unit.

Each rewinder unit may comprise a body containing a power unit and a driving shaft, upon 30 which is mounted a rotary driving member adapted to be moved into driving engagement with any of the bobbins or yarn carriers.

Each rewinder unit may be provided with means for centring the unit in relation to the bobbin or yarn carrier and such means may incorporate 35 a hollow member having a tapering mouth for the purpose of rapidly engaging over the ends of the pegs supporting the bobbins or yarn carrier on the creel.

40 The driving member of each rewinder unit may be made of rubber or other suitable material capable of providing a contact drive.

The yarn carriers may be in the form of bobbins, or cheeses, which latter consist of yarn usually wound upon a cardboard tube which may project slightly at each end. In either case but particularly when cheeses are used, the yarn carrier may project above the supporting peg and the latter may be provided with a metal flange or plate upon which the yarn carrier rests. The flange or plate may be adapted to revolve freely either with the peg or separately from the peg which may be a fixture. When the yarn carrier projects above the top of the peg a modified form 45 of driving unit may be used which may consist of

an inverted cone which can be made to engage with the interior of the upper end of the cardboard or other tube in the cheese, or in a suitable recess in the end of a bobbin or other yarn carrier.

Referring to the drawings:

Figure 1 is a perspective view showing the creel or table upon which a large number of yarn carriers are supported for rotation and also showing a pair of rewinder units and the means by which they are supported.

Figure 2 is a sectional view showing a portion of the creel and two of the bobbins.

Figure 3 is a sectional view showing a portion of the creel upon which are mounted a pair of cheeses.

Figure 4 is a view in side elevation showing one of the rewinder units and the means by which it is suspended.

Figure 5 is a sectional view showing the driving and centring means of the rewinder unit.

Figure 6 is a sectional view showing an alternative form of driving member employed for rewinding.

In the construction shown in Figures 1, 2, 4 and 5 the table 10 is provided with a large number of upwardly projecting spaced pegs 11 upon each of which is mounted a bobbin 12 carrying the yarn.

The spool is shown at 13 and the comb through which the yarns are taken is shown at 14. Between the rows of bobbins, bars 15 are provided to keep the loose ends of yarn above the bottom ends of the bobbins.

The creel is provided with two upwardly projecting posts 16 carrying a rectangular frame 17 and each of the side members of the frame 17 is provided with a T section rail 18 having stops at its ends. Each of the rails is provided with a carriage 19 having rollers 20 and suspended from this carriage by means of a coiled spring 21 is the rewinder unit shown generally at 22. The rewinder unit is provided with a link 23 by which it is suspended from the spring 21. Other forms of flexible and elastic members may be used for supporting the rewinder units.

The body of each rewinder unit contains a power unit which may take the form of a small electric motor or of a small motor adapted to be driven by compressed air or water power or the driving shaft 24 of the power unit may be adapted to be driven by a flexible shaft driven by a suitable motor (not shown).

If the body of the rewinder unit contains a power unit, the power unit is adapted to be switched on or placed in operation by a lever 25 pivoted at 26 to lugs 27 on the body. The lever 25 may be acted upon by a spring so that normally the power is switched off or interrupted. In practice, however, the body of the rewinder 22 is grasped by the operator who at the same time grasps the lever 25 and moves it towards the side of the body of the rewinder 22, thus switching on the power and driving the driving shaft 24.

In the construction illustrated the rewinder unit is driven by a small electric motor contained in the body of the unit and the current is brought to this electric motor by the cable 28.

In the construction shown there are two rewinder units, one suspended above each side of the creel and the two cables 28 may be taken upwardly to a central bar 29 on the frame 17 from whence they are taken to a source of electric supply.

Fixed on the driving shaft 24 is a metal sleeve

75

30 within which are two ball bearings 31 which are spaced apart by a distance tube 32 and mounted within these bearings is a centralising member 33, this centralising member having a tapering mouth 34 so that it can readily be engaged over the upper end of any of the pegs 11.

The sleeve 30 at its lower part is shouldered as shown at 35 and fitting against this shoulder is a rubber tube 36 which constitutes the driving member. The lower end of the rubber tube extends below the centring member 34 and the edge 37 of the lower end of the rubber tube may be beaded and is adapted to engage the top of the bobbin and to drive it, there being sufficient friction between the rubber member and the material of the bobbin to effect a driving connection.

Referring to Figure 3 the pegs for supporting the yarn carriers are shown at 38 and in this construction the yarn carriers are formed as cheeses, each having a central tube 39 which projects through the end of the winding, the tube 39 usually being made of cardboard.

When cheeses are used the short pegs 38 are provided with metal plates or flanges 40 which if desired may be mounted so that they are free to rotate either with the pegs or separately from the pegs which may be fixed.

In carrying out the invention it is necessary to identify each bobbin of yarn carrier and for this purpose the upper ends of the pegs 11 are numbered. When cheeses are used, however, the supporting pegs may be shorter and may not project above the upper ends of the cheeses. To provide the identification of each yarn carrier a numbered peg 43 may therefore be mounted on the creel adjacent each of the pegs 38, or alternatively the number or identifying particulars may be marked on the surface of the creel adjacent each yarn carrier.

The driving unit shown in Figure 5 may not be suitable for winding cheeses and may be replaced by the driving unit shown in Figure 6. In Figure 6 the shaft 24 is provided with a head 44 to which is clamped by a nut 45 an inverted conical member 46 which may be made of rubber or any other suitable material and is adapted to engage within the upper end of the tube 39.

In operation, after a spool has been wound, the operators, usually one at each side of the creel, bring the rewinding units into action successively upon those bobbins or yarn carriers which are to be changed. Upon being released each rewinder unit automatically stops and returns to a position above the tops of the bobbins or yarn carriers. They are easily moved along the creel and also across the creel and they can be brought downwardly to engage any of the bobbins or yarn carriers by the exercise of a little downward pressure which expands the spring 21.

The following are the main advantages obtained by the use of the present invention:

(1) Rewinding done by power driven units saves operator's time.

(2) It eliminates the fatigue of manual rewinding.

(3) When bobbins or other yarn carriers are rewound by hand the loose end of the yarn tends to cling to the other yarn on the bobbin or yarn carrier and is often difficult to find, but the speed of rewinding by power causes the loose end to stand out from the bobbin or yarn carrier so that when next that bobbin or yarn carrier is required, the end is quickly and easily grasped by the operator.

What we claim then is:

1. A rewinder for rotary yarn carriers comprising a body, a power driven driving shaft in the body and protruding therefrom, a driving member consisting of a sleeve mounted on the driving shaft and having a tube of soft elastic material, the edge of which is disposed below the end of the sleeve and is adapted to engage an end of the yarn carrier.

2. A rewinder for rotary yarn carriers each rotatably mounted on a peg comprising a body, a power driven driving shaft in the body and protruding therefrom, a driving member on said driving shaft and consisting of a sleeve on which is fitted a tube of soft elastic material, the edge of which is disposed below the end of the sleeve and is adapted to engage an end of the yarn carrier, a bearing fixed in the sleeve and a centralising member mounted in said bearing, said centralising member having a tapering mouth for engaging over the peg on which the yarn carrier is mounted.

3. A rewinder for rotary yarn carriers each rotatably mounted on a peg comprising a body, a power driven driving shaft in the body and protruding therefrom, a driving member on said driving shaft consisting of a sleeve on which is fitted a tube of soft elastic material, the edge of which is disposed below the end of the sleeve and is adapted to engage an end of the yarn carrier, said sleeve having an external shoulder against which one end of said tube engages, a bearing in the sleeve and a centralising member in the bearing, said centralising member having a tapering mouth for engaging over the peg on which the yarn carrier is mounted.

4. A rewinder for rotary yarn carriers each rotatably mounted on a peg comprising a body, a power driven driving shaft in the body and protruding therefrom, and a driving member on said driving shaft consisting of a sleeve on which is fitted a tube of soft elastic material, the edge

of which is disposed below the end of the sleeve and is adapted to engage an end of the yarn carrier, spaced bearings in the sleeve and a centralising member having a shouldered parallel portion engaging in said bearings and having a tapering mouth for engaging the peg on which the yarn carrier is mounted, the open end of said mouth being disposed between the end of the sleeve and the end of the tube.

5. Rewinding gear for a plurality of yarn carriers mounted for rotation on a creel comprising a rail fixed above the creel, a carriage on the rail, a flexible and elastic suspension member attached to the carriage, and a power driven rewinder unit attached to the end of the suspension member.

10 6. Rewinding gear for a plurality of yarn carriers mounted for rotation on a creel comprising supports extending upwardly from the creel, a frame carried above the creel by said supports, rails on the frame, a carriage on each of said rails, a flexible and elastic suspension member on each of said carriages, and a power driven rewinder unit attached to each of said suspension members.
